CARRIER MEANS FOR A MATCH MACHINE

Edwin Zilver, The Hague, Netherlands, assignor to N. V. Inland, Piekstraat, Rotterdam, Netherlands, a corporation of the Netherlands

Application April 4, 1955, Serial No. 499,103

Claims priority, application Netherlands April 7, 1954

4 Claims. (Cl. 144—65)

This invention relates to an element for a carrier means for a match machine and to a carrier means for a match machine respectively and its object is to provide a carrier means of this kind in which not only the matches are firmly held but by means of which it is also possible to transport matches of different thickness or matches of a different kind, such as wooden matches, paper matches and wax matches.

This object is achieved by the carrier means according to this invention in that it comprises one or more resilient means for holding the matches or in that it consists wholly or partly of resilient material. These resilient means may be integral with rigid supporting means, for example in that flexible rubber or the like is used for the resilient means and hard rubber, e. g. ebonite, for the rigid supporting means.

According to the present invention the or each resilient means may be secured to a rigid supporting means in which receiving spaces are provided allowing the passage of the matches. These resilient means may be vulcanized to the said rigid supporting means or fixed thereto in some other way.

Instead of one supporting means only which may be embedded, if required, in the rubber, the or each resilient means may also be disposed between two rigid supporting means both having receiving spaces permitting the passage of the matches.

These receiving spaces may have inwardly tapering edges. In this way small deviations in the position of the matches are met when these are inserted into the said spaces.

According to this invention the receiving spaces may have a round, square or other cross section. These receiving spaces may also be slot-like or may be formed by intermediate spaces between parts of the rigid supporting means.

When the matches are inserted into the holes of the carrier means elements, it is necessary that these elements are always in a predetermined position in front of the reservoir containing the match splints. It is, therefore, necessary that these elements cannot assume an oblique position in their guides which would, moreover, create the risk of these elements getting stuck in the guides. The present invention avoids this risk in that the rigid supporting means is provided at each of its ends with a rotatable guide roller, a rounded portion or the like.

According to this invention the or each resilient means may comprise one or a number of strips of rubber or like material which is or are provided with spaces for receiving the matches, these spaces facing the receiving spaces, intermediate spaces or holes of the or each supporting means.

These receiving spaces may, according to the invention, be formed by holes or slots provided in the or each resilient means, and these resilient means may also be

2

so spaced that receiving spaces are formed between them for holding the matches. Obviously, these resilient means should be united with the or each rigid supporting means in such a way that a strong unit is produced.

According to this invention each resilient means may consist of a piece of rubber or like resilient material provided with a hole. These pieces may be made, for instance, by cutting rings from a tube, these rings being secured to a supporting means or between two plates or strips of a supporting means.

Instead of using resilient means made from resilient material, the resilient means according to the invention may also each consist of two springs having openings facing each other and forming aligned receiving spaces for the matches. Also helically wound springs may be used, the matches being held between the coils.

For the purpose of conveying these elements recesses may be provided in each carrier means near the ends of the longitudinal sides, these recesses co-operating with the mechanism driving the carrier means.

The invention will be described below with reference to the accompanying drawings showing by way of example some embodiments of the element according to the present invention.

Fig. 1 shows a top plan view of an element of which the right hand end is provided with a guide roller and the left hand end is rounded off.

Fig. 2 is a longitudinal section through part of an element having two supporting means.

Fig. 3 is a longitudinal section through part of an element having one supporting means only.

Fig. 4 is a longitudinal section through part of another embodiment of an element.

As may be seen from Figs. 1 and 2 the element comprises a top plate 1 and a bottom plate 2 between which a resilient means 3 of rubber, artificial rubber or some other resilient material has been provided. The top and bottom plates are provided with several rows of equally spaced holes 4, 5. The outer ends of these holes have conical shapes. Holes 6 have also been provided in the resilient means 3. The cross section of the holes 6 is smaller than that of the holes 4 and 5 so that a match splint passing with some clearance through the holes 4 and 5 is held in the holes 6. The ends of the top plate and the bottom plate are secured to one another by means of rivets 7, an intermediate element of metal being provided in that place between these two plates. In the right hand intermediate element a recess 9 is provided in which a roller 10 rotatable on a shaft 11 is arranged. The left hand intermediate element and the left hand ends of the plates 1 and 2 have a convex shape. The roller 10 and the convex end portion of the element serve to prevent the element from getting stuck in the guides of the carrier means so that this element will always have the correct position at the point where the match splints are inserted into the holes of this element or are removed therefrom.

Fig. 3 shows a longitudinal section through part of an element having only a top plate 12. This top plate is bent at its ends in order to form a space for accommodating a guide roller 13 and an intermediate element 14. A means 15 consisting of rubber or some other resilient material has been vulcanized to this top plate 12. Holes 16 are provided in the resilient means 15 and holes 17 in the top plate 12, these holes being shaped in the same way as the holes 4 and 6 in the embodiment according to the Figs. 1 and 2.

Fig. 4 shows part of an embodiment of an element in which between a top plate 18 and a bottom plate 19 portions 20 of rubber or some other resilient material are provided, each of these portions having a hole 21,

These holes 21 are in alinement with the holes 22 and 23 of the top and bottom plate.

It is obvious that this invention is not restricted to the embodiments described above and shown in the drawings or to the materials used as described above, but that these may be modified in many ways without departing from the scope of the invention.

I claim:

1. A carrier bar for carrying and conveying splints in match making machines, comprising at least one rigid supporting plate having rows of perforations that freely receive match splints and a strip of resilient material fixedly superimposed on one face of the plate and having holes in registry with the perforations for clampingly receiving the match splints, said holes being of a cross-sectional area that is less than the cross-sectional area of the perforations.

2. A carrier plate as claimed in claim 1, wherein the strip of resilient material is vulcanized to the rigid supporting plate.

3. A carrier bar for carrying and conveying splints in match making machines, comprising a pair of spaced apart, confronting rigid supporting plates, said plates

having aligned perforations formed therein to allow the free passage of match splints therethrough, a strip of resilient material fixed between the plates and provided with holes in registry with the perforations, said holes being of a cross-sectional area less than the cross-sectional area of the perforations and the area being such that matches of different sizes are held therein.

5 4. A carrier bar as claimed in claim 3, wherein said strip is composed of abutting separate sections of resilient material.
